CLAIM

The ornamental design for a warmer for medical pads, as shown and described.

DESCRIPTION

FIG. 1 is a perspective view of the warmer for medical pads of the instant invention with the hinged lid in a raised position;

FIG. 2 is a perspective view with the hinged lid in a closed position;

FIG. 3 is a front elevational view thereof;

FIG. 4 is a rear view thereof;

FIG. 5 is a right side view thereof;

FIG. 6 is a left side view thereof

FIG. 7 is a top plan view thereof; and,

FIG. 8 is a bottom plan view thereof.

The broken line showing of the feet and rear access panel of the warmer for medical pads is for illustration purposes only and forms no part of the claimed design.
